UNITED STATES PATENT OFFICE.

FRANCIS HODGKINSON, OF PITTSBURGH, PENNSYLVANIA, ASSIGNOR TO WESTINGHOUSE ELECTRIC & MANUFACTURING COMPANY, A CORPORATION OF PENNSYLVANIA.

TURBINE-STATOR.

1,264,648.

Specification of Letters Patent. Patented Apr. 30, 1918.

Application filed September 3, 1915. Serial No. 43,863.

To all whom it may concern:

Be it known that I, FRANCIS HODGKINSON, a subject of the King of Great Britain and Ireland, a resident of Pittsburgh, in the 5 county of Allegheny and State of Pennsylvania, have made a new and useful Invention in Turbine-Stators, of which the following is a specification.

This invention relates to turbines and has 10 for an object to produce improved means whereby close clearances may be maintained between the rotor and stator elements without the danger of contact due to variations in the relative positions of the elements.

15 A further object is to produce means for preventing relative radial motion of the rotor element of a turbine with relation to the stator element.

These and other objects, which will be 20 made apparent throughout the further description of the invention, are attained by means of apparatus embodying the features herein illustrated and described.

In the drawings, Figure 1 is a sectional view of the end portion of a turbine equipped 25 with an embodiment of my invention.

Fig. 2 is a fragmental end elevation of the 30 turbine illustrated in Fig. 1, portions being shown in section for convenience of illustration.

In some forms of turbines it is customary 35 to form the bearing support integrally with the turbine stator or casing, and in large turbines there is a tendency for the support to shift its position due to temperature strains in the supporting portion of the stator, or due to the normal strains on the support. This tendency is greatest at the 40 exhaust end of the turbine because of the necessity for providing the large exhaust passages, the arrangement of which is such that it is difficult to construct a rigid bearing support without unduly increasing the weight of that portion of the stator supporting the 45 bearing support. The variations in temperature at the exhaust end of the turbine are also great and this adds to the difficulty of producing a rigid support, and in addition to this the external pressure of the atmosphere on the very large exhaust chambers 50 tends to produce deformation.

The more or less specific object of my invention is to produce simple and effective means for bracing the bearing supporting 55 portion of the stator so that the bearing

support is held stationary with relation to the cylindrical portion of the stator, or that portion which encircles the rotor. The broad underlying principle of the invention, however, is to increase the rigidity of the structure, so that the bearing support is positively held in place under varying strains and varying temperature conditions. It will be apparent that my invention may be employed in connection with the bearing or bearing 60 support at the high pressure end of a turbine, and it may be also employed in connection with turbines in which the bearing support is formed separately of the stator.

In the drawings I have illustrated the end 70 portion of a turbine stator 3, which, as illustrated, is divided into an upper and lower section along a horizontal plane passing through the axis of the rotor. The two sections are adapted to be bolted or otherwise 75 secured together so that they coöperate in inclosing the rotor and also in forming a support for the bearings of the rotor. The casting illustrated is provided with a cylindrical portion 4, which surrounds the rotor and on 80 which radial blades (not shown) are mounted. The clearance between this portion of the stator and the working elements of the rotor is preferably small and consequently it is desirable, and in fact necessary, to prevent the rotor from moving radially with relation to this portion of the stator, since 85 contact between the rotor elements and the stator is likely to damage, if it does not wreck, the turbine.

This portion 4 of the stator communicates with the exhaust end of the turbine which is enlarged to form an exhaust chamber 5, in direct communication with an exhaust port 6, with which the stator is provided. The end wall 7 of the lower section of the stator and the end wall 8 of the upper section coöperate in supporting a bearing support 9, which is formed integrally with the lower section. The arrangement of the 90 exhaust chamber 5 within the casing necessitates a construction of the bearing support such that its inner end overhangs the supported portion of the end wall 7. While the upper section of the casing aids somewhat in 95 supporting the bearing support, its form is such, due to the necessity for providing the exhaust chamber 5, that it does not add materially to the rigidity of the support. In order to hold the support stationary with re- 100

lation to the cylindrical portion 4 of the stator, I employ a series of radial stay bolts or struts 10 and a series of longitudinally extending stay bolts or struts 11 between the 5 cylindrical portion 4 and the end walls 7 and 8 of the lower and upper sections of the stator. In this way I brace the end walls and increase their rigidity. In addition to this, the braces are so arranged that the portions of the end walls most likely to distort 10 by reason of temperature, normal strains, or atmospheric pressure, are supported in two directions by the cylindrical portion 4.

As illustrated, each stay bolt 10 and 11 15 consists of a tension bolt 12 which is surrounded by a compression sleeve 13. One end of the bolt is screwed into or otherwise secured to the cylindrical portion 4 and the other end projects through the end wall of 20 the casing and is provided with a nut. A spacer or compression sleeve 13 surrounds each bolt and is located between bosses formed on the end wall of the stator and the cylindrical portion 4, and is of such length 25 that it maintains the desired relative positions between the end wall and the cylindrical portion 4 when the nut on bolt, surrounded by it, is tightened. In this way the end wall of the casing is stayed or held 30 rigidly with relation to the cylindrical portion 4, and consequently the tendency of the bearing support 9 to shift its position relatively to the cylindrical portion is materially lessened. In the drawings the radially 35 extending braces are provided for the upper section of the casing only, while both the upper and lower sections are provided with the longitudinally extending braces. As 40 illustrated, the upper section of the casing is also provided with one or more radially extending webs 15, preferably spaced between adjacent stays 10, and the lower section is provided with a vertical web 16 which is formed integrally with the end 45 wall 7, and extends from the supported portion of that wall upwardly to the overhanging end of the bearing support 9. The principal feature of the invention, however, is the bracing of the end walls of the upper 50 and lower sections from the cylindrical portion 4 of the stator for the purpose of increasing the rigidity of the end walls.

What I claim is:

1. In combination with the stator of a 55 turbine, a bearing support formed integrally with the stator and stiffening braces located inside of the stator between the cylindrical portion of the stator and the portion thereof supporting the bearing support.

60 2. In combination with a turbine stator,

divided into an upper and a lower section, a bearing support integrally formed with the lower section of the stator, and stiffening braces between the semi-cylindrical portion of the upper section and the end portion 65 thereof.

3. In combination with the stator of a turbine, a bearing support integrally formed therewith and a series of stay bolts between the cylindrical and the end portion of the 70 stator, said bolts being located within the interior of the stator.

4. In combination with a turbine stator, divided into an upper and a lower section, a bearing support, supported by the stator, 75 stiffening braces between the cylindrical portion and the portion of the stator supporting the bearing support and means for rigidly securing the upper and lower sections together.

5. In combination with a turbine stator, having an exhaust chamber formed in one end thereof, a bearing support supported by the end portion of the stator, and longitudinally and radially extending stay bolts, 85 between the end portion and the cylindrical portion of the stator.

6. In combination with a turbine stator, comprising a cylindrical portion and an enlarged end portion, radially and longitudinally 90 extending stay bolts between the cylindrical and the end portion of the stator for supporting the end portion of the stator.

7. A turbine stator, comprising a cylindrical portion and an enlarged end portion 95 inclosing an exhaust chamber, said stator being formed in upper and lower sections, in combination with a bearing support formed integrally with the lower section and at the end portion thereof, and radially 100 and longitudinally extending struts between the cylindrical and the end portion of the upper section of the stator.

8. In combination, a stator of a turbine having a cylindrical blade carrying portion 105 projecting into the exhaust portion of the stator, and stiffening braces between the cylindrical blade carrying portion and the shell of the exhaust portion of the stator.

9. In combination, a stator of a turbine 110 having a cylindrical blade carrying portion projecting into the exhaust portion of the stator, and stiffening braces and webs between the cylindrical blade carrying portion and the shell of the exhaust portion of the 115 stator.

In testimony whereof, I have hereunto subscribed my name this 31st day of August, 1915.

FRANCIS HODGKINSON.
